UNITED STATES PATENT OFFICE.

JOHN S. KUDLA, OF LOS ANGELES, CALIFORNIA.

DEVICE FOR TREATING THE EAR.

Application filed April 18, 1922. Serial No. 555,125.

To all whom it may concern:

Be it known that I, JOHN S. KUDLA, a citizen of Czechoslovakia, residing in the city and county of Los Angeles and State of California, have invented a new and useful Device for Treating the Ear, of which the following is a specification.

This invention relates to a method and means for treating the ear, and has for its object the cure of deafness, of ear-ache, and other diseases and afflictions of the ear.

A further object of this invention is to cure abscesses of the ear, and to remove hardened ear-wax and foreign substances from the ear, and to give relief from gatherings in the ear.

Heretofore in the treatment of diseases of the ear, the method usually employed by physician, is to insert probing implements in the ear, thereby causing discomfort and annoyance to the person operated upon, and in some cases, causing injury to the ear passage by the pressure from the probe and other instruments.

I avoid all these objections in the treatment of the ear, by the use of my improved device and the method of using the same.

The device illustrated herein and embodying my invention is quick to manipulate, simple to construct, and is well adapted to serve the purposes for which it is intended.

In the drawings: Figure 1 is a perspective view of my improved device for treatment of the ear. Fig. 2 is a perspective view showing the device applied to the ear and in use.

Referring to the drawings, my device for treating the ear consists of a hollow cone 11, having a body 12 open at each end, and made preferably of a light but closely woven cloth fabric 13, coated with wax 14. The wax is medicated, and may contain any preferred substances which would be of benefit in treating the ear. The small end 15, is of a size allowing the same to be inserted in the ear a sufficient depth so that the air within the cone cannot escape therefrom, after the device has been applied for use.

In constructing this device, I use a light weight cloth fabric having a close weave, so that the air when heated within the cone cannot readily escape therefrom. This cloth fabric is wrapped in one or more layers to form a cone. The cloth is very lightly impregnated with a wax substance, preferably candle wax, to which has been added the

medicinal agents desired. The cone, after being formed, is then given an additional and very thin coat of the wax.

In my improved method for treating the ear, I first place in the ear a small quantity of pure olive oil which may be left in the ear for a short time, and serving to soften the ear-wax, or any similar substance, but in many cases the irrigation of the ear with the olive oil may be dispensed with if desired. The next step in treatment of the ear consists in inserting the cone within the ear, and then lighting the outer end of the cone and allowing the same to burn to within two inches of the ear. The burning wax creates a medicated smoke within the cone, and this is driven into the ear, and, in connection with the heat generated by the combustion of the wax, the ear-wax and other substances within the ear, will be drawn into the small end of the cone. At the normal rate of combustion of the wax, the same will require about ten minutes to reach to within two inches of the ear. Upon the initial combustion, the wax being burned from the cloth fabric, the cone will collapse at the outer end and thus close the open bore of the cone. Further combustion of the wax and collapsing of the cloth fabric serves to drive the heated air and smoke into the ear, and this, combined with the generated heat, serves to fully clean the ear, and is effective alike, for cure of surplus ear wax, deafness, gatherings and abscesses, and for removing foreign substances from the ear. This treatment is painless, and all danger of injury to the ear is eliminated by its use. When the wax component of the cone has been burned from the cloth fabric to within two inches of the ear, the cone is then removed from the ear. For each treatment of the ear, a new cone is required.

What I claim is:

1. An instrument for treatment of the ear, which consists of a hollow cone having the apex of a size to enter well within the ear, and formed from a light and tightly woven cloth fabric, and a coating of combustible wax on the cloth fabric.
2. A device for treatment of the ear, consisting of a cloth fabric cone, having open ends and a hollow interior, a combustion wax incorporated with the cloth fabric, and a coat of wax on the exterior of the cone.
3. A device for treatment of the ear consisting of a waxed cloth fabric cone having

- a hollow interior and open ends, and adapted to collapse upon combustion of the wax.
4. A waxed cloth fabric cone, adapted for insertion in the ear, and collapsible upon combustion.
5. A device for treatment of the ear, consisting of a waxed cloth fabric cone having a hollow interior and open base and apex, and adapted for insertion within the ear, and adapted to collapse upon combustion of the wax component of the cone.
6. A device for treatment of the ear, consisting of a fabric cone, and a medicated wax coating on the fabric.

7. A device for treatment of the ear, consisting of a fabric cone, and a medicated wax coating on the fabric and adapted for slow combustion.

8. A cloth fabric cone having a hollow interior, and a coat of combustible wax on the fabric, said fabric collapsing under combustion of the wax coating, and thereby serving to force the heat generated by the combustion, into the ear.

In testimony whereof, I hereunto affix my signature.

J. S. KUDLA.
